US00D843596S

(12) **United States Design Patent** (10) **Patent No.:** **US D843,596 S**
(45) **Date of Patent:** **** Mar. 19, 2019**

(54) **ULTRASOUND APPLICATOR**

(71) Applicant: **AxioSonic, LLC**, Effingham, IL (US)

(72) Inventors: **Peter M. Bonutti**, Manalapan, FL (US);
Justin E. Beyers, Effingham, IL (US);
Tonya M. Bierman, Dieterich, IL (US);
Melvin Joshua Leedle, Bridgeton, MO
(US); **Bryce G. Rutter**, St. Louis, MO
(US)

(73) Assignee: **AXIOSONIC, LLC**, Effingham, IL
(US)

(**) Term: **15 Years**

(21) Appl. No.: **29/556,129**

(22) Filed: **Feb. 26, 2016**

Related U.S. Application Data

(63) Continuation of application No. 15/011,156, filed on Jan. 29, 2016, which is a continuation of application No. PCT/US2015/010843, filed on Jan. 9, 2015.

(51) **LOC (11) Cl.** **24-99**

(52) **U.S. Cl.**

USPC **D24/231; D24/133**

(58) **Field of Classification Search**

USPC D24/231, 186, 144, 187, 158, 169, 133,
D24/209; 601/2

(57) **CLAIM**

The ornamental design for an ultrasound applicator, as shown and described.

DESCRIPTION

FIG. 1 is a perspective of an ultrasound applicator of our new design;

FIG. 2 is a front elevation view of the ultrasound applicator;

FIG. 3 is a right elevation view of the ultrasound applicator;

FIG. 4 is a top plan view of the ultrasound applicator;

FIG. 5 is a rear elevation view of the ultrasound applicator;

FIG. 6 is a left elevation view of the ultrasound applicator; and,

FIG. 7 is a bottom plan view of the ultrasound applicator. Features forming no part of the claimed design are illustrated in broken lines.

1 Claim, 7 Drawing Sheets
